UNITED STATES PATENT OFFICE.

WILLIAM H. ASCUE, OF KIOWA, KANSAS.

GRAIN-DOOR.

No. 873,115.

Specification of Letters Patent.

Patented Dec. 10, 1907.

Application filed August 17, 1907. Serial No. 389,020.

To all whom it may concern:

Be it known that I, WILLIAM H. ASCUE, a citizen of the United States, residing at Kiowa, in the county of Barber and State of 5 Kansas, have invented certain new and useful Improvements in Grain-Doors, of which the following is a specification.

This invention is a grain-door for cars, granaries and the like, and has for its object 10 to provide a door which will effect a grain-tight closure, and one which is simple in construction, and can be easily opened and closed.

In the accompanying drawing, Figure 1 is 15 a transverse sectional view of the door closed. Fig. 2 is a similar view showing the door open. Fig. 3 is a longitudinal section on the line 3—3 of Fig. 1. Fig. 4 is a horizontal section on the line 4—4 of Fig. 1. Figs. 5, 6, 20 and 7 are details showing the apparatus for starting the opening movement of the door. Fig. 8 is a detail showing the door construction.

Referring specifically to the drawings, 10 25 denotes the floor of a freight car, and 11 are the side walls thereof having doorways the jambs of which are indicated at 12.

To the door-jambs 12 on the inside of the car are secured runways or tracks 13 and 30 under the roof of the car are continuations of said runways, consisting of channel-beams 14 extending in a curve to the top ends of said runways. The channel-beams 14 are secured to the roof by hangers 15. The run- 35 ways 13 are provided with a shield 16 hinged to one edge thereof as indicated at 17 and provided with a pivoted latch 18 for holding the same closed.

The door comprises a series of sheet-metal 40 sections 19 which are connected at their longitudinal edges by hinges, the pintles of which are indicated at 20. At the ends of the doors are slots in which are mounted rollers 21 whereby the doors are slidably 45 mounted on the runways 13 and 14. The pintles 20 extend across the slots and serve as axles for the rollers. The doors and runways are the same on both sides of the car.

On the outside of the sections 19 are longitudinal flanges 22 to brace and stiffen the same, and prevent bulging out from the weight of the grain.

When the doors are closed their outer edges and the rollers 21 are inclosed by the

shields 16 which makes a grain-tight closure. 55 The doors are opened by sliding them upwardly on to the runways 14 which are superposed in order that the doors may not interfere with each other. The doors can be removed from the doorway upon swinging 60 the shields 16 open.

Any suitable means may be employed for elevating the doors. I have shown shafts 23 mounted in bearings at the top of the doorways. On the shafts are wound cables 65 24 connected to the top edge of the doors. A worm gear 25 is employed for turning the shaft, and a pawl and ratchet mechanism 26 is provided for preventing back slip.

To start the door a lifting jack is provided 70 which is connected to the outside of the door and is foldable thereagainst so that it may travel with the door when it is elevated to the runway 14.

The jack comprises a lever 27 pivoted at 75 28 to a support 29 which is pivotally mounted in a bracket 30 secured to the door on the outside thereof. The fulcrum of the lever is a frame comprising two spaced plates 31 having a toothed slot 32. The lever extends 80 between the plates and has pins 33 projecting from its sides which are engageable with the teeth of the slot 32. When the jack is not in use, the fulcrum frame is swung around 85 so that the lever extends therebetween and the jack is then swung against the side of the door as shown in Fig. 7, so as to be out of the way. A catch 34 is provided for holding the jack in this position. When the jack is to be used, it is released from the catch and 90 swung outwardly from the door. The fulcrum frame is then turned and placed on the floor of the car as shown in Figs. 5 and 6 after which the lever can be operated in an obvious manner. 95

In the drawings the invention is shown applied to a grain-car but it can also be applied to granaries, bins, etc., as well as to cars carrying coal or other loose material. The doors work easily, are strong and durable, and simple in construction, and they afford a tight closure. 100

I claim:

1. The combination with a door-frame having runways; of a sliding door having 105 rollers at its ends traveling on the runways; and a shield hinged at one edge adjacent the runways and extending in a bend around the

rollers, and at its opposite edge in sliding contact with the door.

2. The combination with a door-frame having grooved runways on the inner face of the jambs; of a sliding door having rollers at its ends traveling in the grooves of the runways; and a shield hinged at one edge adjacent the runways, and extending in a bend

around the rollers, and at its opposite edge in sliding contact with the door. ¹⁰

In testimony whereof I affix my signature, in presence of two witnesses.

WILLIAM H. ASCUE.
